FERTILIZER SPREADER

Loren E. Tyler, 1110 Atlantic Ave., Benson, Minn.

Filed Mar. 26, 1962, Ser. No. 69,427

Term of patent 14 years

(Cl. D35—2)

FIG. 2

FIG. 1 is a front perspective view of a fertilizer spreader illustrating my new design; and

FIG. 2 is a rear perspective view thereof.

I claim:

The ornamental design for a fertilizer spreader, as shown.
